UNITED STATES PATENT OFFICE.

MARTIN V. HAMMACK, OF THALIA, VIRGINIA, ASSIGNOR OF ONE-HALF TO
HARRY W. MILLER, OF THALIA, VIRGINIA.

GAME APPARATUS.

SPECIFICATION forming part of Letters Patent No. 697,406, dated April 8, 1902.

Application filed September 5, 1901. Serial No. 74,352. (No model.)

To all whom it may concern:

Be it known that I, MARTIN V. HAMMACK, a citizen of the United States, residing at Thalia, in the county of Princess Anne and State of Virginia, have invented certain new and useful Improvements in Game Apparatus, of which the following is a specification.

My said invention consists in certain improvements in the construction and arrangement of parts of a game apparatus by which a number of games, hereinafter described, may be played with the use of a single apparatus and the table also used for other purposes, as a "center-table," when not in use for playing purposes, as will be hereinafter more fully described and claimed. I have denominated this apparatus the "star" game-board.

Referring to the accompanying drawings, which are made a part hereof, and on which similar reference characters indicate similar parts, Figure 1 is a top view, slightly in perspective, of a table forming part of my said apparatus. Fig. 2 is a side elevation of the same; Figs. 3 and 4, top plans illustrating different games; Fig. 5, a sectional view of the spring driver or cue. Fig. 6 is a view of another form of cue for use with the apparatus; Fig. 7 a view of one of the balls used in the game, and Fig. 8 a view of the disks used in one of the games.

In said drawings the portions marked A represent the body or central portion of the table; B, leaves hinged thereto; C, the spring-cue, and D the rigid cue.

The construction of the central portion of the table A is not material, being appropriate for the purpose, and preferably hexagonal in shape, mounted on a suitable frame, supported on legs in the usual or any desired manner, the legs being preferably removable for convenience in packing for shipping. It is provided with a drawer or drawers A', in which may be stored the balls, disks, cues, and other parts used in playing the games. Its top has a star-shaped diagram within a six-inch circle in its center, surrounded by rings of regular width, the rings being arranged of different colors, preferably red, white, and blue, as indicated, the first outside the star-circle being red, the next white,

and the next blue, the width of each ring being three inches. The remainder of the surface is white, including the part within the star-circle, except the star-points, which are alternately red and blue. At the center of the star is a three-inch white ring in the center of which is formed a shallow depression 1 of just sufficient depth to steady a ball therein, and at the end of each star-point is a similar depression 2.

The leaves B are hinged one to each of the six sides of the top A and are of a width at the base corresponding to the width of the side of said top, to which they are hinged, and run to a point or nearly a point at the outer end, forming, when raised, substantially the points of a star and making a star-shaped table. At the point of each of said leaves is mounted a pocket B', of the same general character as the pockets of a pool-table, or any pocket adapted to receive the projectile used in playing the games for which the apparatus is designed. Said leaves are alternately red and blue, as indicated, except a six-inch circle in the center of each, which is white and has a star therein formed similarly to the star in the center of the top A, with a three-inch white circle in the center and six star-points, alternately red and blue, extending therefrom to the six-inch circle. A slight depression may also be formed at the center of each and at each point, as in the case of the star at the center of the board, just sufficient to prevent balls placed therein from rolling off without force. Instead of the center-table being six-sided it may be of any other form desired, as round, as indicated by dotted lines in Fig. 4, the pointed leaves being hinged or otherwise suitably attached thereto. Around the outside edges of said leaves is secured a flange b' to prevent the balls from rolling off, and these may be formed as cushions, if desired, and the sides of the leaves are preferably somewhat curved, as shown, to give the balls striking them guidance to the pockets B'. In mentioning dimensions in this description it will be understood that I do not intend to limit myself to any dimensions, but only mention the proportions of the diagrams of what I consider a standard table of the character mentioned of the size de-

signed for parlor use. Tables of other sizes and other dimensions may be found desirable, however, for special uses, and I design to make a very small table on the same plan for the use of children as a toy.

5 The spring-cue C extends through a casing C', having a knob c on its outer end and a coiled spring c', connected at one end to said knob and at the other end to a center bearing-piece c² in the opposite end of casing C'. The use of the cue is well understood and needs no special description.

10 The cue D is simply a straight rod with a striking end d, having an inwardly-curved 15 face.

The board, as will thus be seen, is built in the form of a star and may be in the form of a table, as shown, or in the form of a board to be placed upon a table or suitable support. 20 I prefer the table form with hinged or detachable leaves, so that when not in use for playing it may be utilized as a table, and thus avoid the necessity of putting it away and getting it out every time it is used. It will

25 be understood that the surface may be of any desired character, polished or covered with soft material, on which the stars are represented in any desired manner. The colors red, white, and blue described may be varied, 30 of course; but I prefer the design described, the leaves being alternately red and blue and the colors across the top red, white, and blue in regular order, with the balls and disks made to correspond, as hereinafter pointed out.

35 The games played are all denominated "star" games, being played upon the star game-board and involving features which are based upon the star form in some particular.

In Fig. 1 I show on one of the stars of one 40 of the leaves seven men or pins p, located with red pins on the red points, the blue pins on the blue points, and a white pin in a white center, and on the opposite side of the board a play or star ball 3 is located on the outside 45 point of the star. The game is to knock down the pins with the ball by a blow thereon with the spring-cue C, held in the player's hand. To knock down the seven pins with one play is called a "star" play and counts fifty. To 50 knock them all down with two plays is called a "semistar" play and counts twenty-five; otherwise each pin knocked down counts two and the center one three. Three plays are allowed each player at a turn, and a game 55 may be any number of points agreed upon, as one hundred, two hundred, &c. This game I have denominated "star seven-pino."

In Fig. 3 there are six balls shown on the points of the star and one in its center, being 60 steadied from rolling out of position by the indentations 1 and 2. The six balls on the points are red and blue and mounted alternately on the point of corresponding color. The red balls I have marked r and the blue balls b, 65 the center ball, which is white, w, and the star or play balls s, the same being preferably

white balls with red and blue stars formed thereon, as indicated in Fig. 7. In this game the star-ball is placed on the outside point of the star on the star-leaf belonging to the 70 player, and the play is to clear the center of all the balls by impelling the same with the spring-cue. If this is accomplished at one play, it counts one hundred and is called a "star" play; if at two plays it is called a 75 "semistar" play and counts fifty; otherwise the red and blue balls driven off the central star count five each and the central or white ball ten. The game may be any number agreed upon, as two hundred, three hundred, &c. This game I have denominated "star-olo." With the same arrangement of balls another game may be played, the object being to put the red balls into the pockets of the red star-leaves, the blue balls into 80 the pockets of the blue star-leaves and leave the white ball undisturbed in its position in the center. The player may place his star-ball in any position on his leaf and impel the same with the spring-cue in the direction he 85 thinks best to accomplish the purpose. Each ball properly located counts five, and if the white ball is left undisturbed it counts twenty. If moved into the six-inch circle, it counts fifteen, into the twelve-inch circleten, and into 90 the eighteen-inch circle five, and into the twenty-four inch circle three, and outside of circles it counts nothing. The game may be played for as many points agreed upon, as one hundred, two hundred, &c. This game I have 95 denominated "star-golo."

Each of these games may be played by as many persons as desired up to six, each having his own star-leaf to play from, to which he is confined. Each may have three of the 105 star-balls for the three plays allowed at one turn and a cue, or they may be passed from one player to the other, as will be readily understood.

"Star-polo" is a name I have given to another game which may be played upon this board. In this game but one ball is used, as indicated in Fig. 4, and each of the six players has a cue D, with the wide inwardly-curved face. Two of the players are called "rushers" and start the ball, the object being for the players on the red leaves to put the ball in the pocket of the blue leaves and those on the blue leaves to keep it from going into their pockets and put it into the red pockets, and vice versa. After the ball is started by the rushers all are then in the game and must guard their pockets and endeavor to get the ball into an opponent's pocket. Each ball put into an opponent's pocket counts one and 120 a game is ten or any number agreed upon.

In Fig. 8 I show a disk d in plan and central section, which may be used in playing another game on this board, which I have denominated "star-colo." Each player has six of 130 said disks, those at the red leaves having red and those at the blue leaves having blue.

The disks being placed in any desired position on the star of the player's leaf, the game is to place that disk within the center of the star of the board A or as near thereto as possible. The players play once at a turn until each have played around six times. After the first play the succeeding players will attempt to remove their opponents' disks from their positions of advantage, as well as to locate their own to count, and will also attempt to knock their opponents' disks into their own pockets. After each play all disks knocked beyond the outside or blue ring or circle and not landed in a pocket are removed, 5 and at the end of the game those remaining counted as follows: All those within the three-inch circle at the center of the board A count twenty-five for the player, all those within the six-inch circle count twenty, all those 5 within the twelve-inch circle count fifteen, all those within the eighteen-inch circle count ten, and all those within the twenty-four-inch circle count five for the side to which they belong, while all those in the pockets count twenty-five each for the opposite side—that is, the reds in the pockets count for the blue 10 players and the blues for the red players. Should a player fail to drive his disk within the twenty-four-inch circle, he may have another trial.

These are a few of a series of star games which can be played upon this star game-board, all interesting and entertaining, requiring considerable skill in properly executing them. It will be understood, of course, that the plan for either game may be varied and that other games may be suggested, all of which can be played upon this board, the description of the games as above being only 15 for the purpose of illustrating the usefulness of the apparatus.

Having thus fully described my said inven-

tion, what I claim as new, and desire to secure by Letters Patent, is—

1. A game apparatus comprising a board in the form of a star the points of which have rests for the cue in playing games thereon, diagrams being formed on the surface of said board in its center and at regular intervals around it, which define the rests for the projectiles, or men, and the counts which are used in the games played thereon, substantially as set forth. 45

2. A game apparatus comprising a board in the form of a star having stars represented on its surface with rests for projectiles at their points and center, the pockets at the points of the star extensions on the table, whereby it is adapted for the playing of games thereon with projectiles and a cue, substantially as 50 set forth. 55

3. A game apparatus comprising a board, projecting leaves hinged to its sides which run to a point, a guide or flange around the sides, pockets in the ends of said leaves, 60 whereby it is adapted for the playing of games thereon with projectiles and cue, substantially as set forth. 65

4. A game apparatus comprising a central hexagon board, pointed leaves attached thereto at each of its sides, means for supporting them, stars formed on the surface of said table in its center and in the center of each leaf, a flange around the edge of said leaves, and pockets in their ends, substantially as set 70 forth. 75

In witness whereof I have hereunto set my hand and seal, at Washington, District of Columbia, this 29th day of August, A. D. 1901.
